2,788,896

APPARATUS FOR GAGING AND CLASSIFYING SHEETS

William E. Coleman, Pittsburgh, Pa., assignor to United States Steel Corporation, a corporation of New Jersey

Application July 28, 1953, Serial No. 370,709

4 Claims. (Cl. 209—82)

This invention relates to apparatus for gaging and classifying sheets such as tin plate. The most common practice in gaging and classifying tin plate is to gage the plate in strip form rather than in sheet form. For such a purpose gages such as shown in the patents to Clapp No. 2,488,269, dated November 15, 1949, and Bernstein No. 2,518,115, dated August 8, 1950, are commonly used. However, these gages present a disadvantage when gaging sheets because there is no means for interrupting the operation of the gage by the sheets. Apparatus has been provided for gaging and classifying sheets such as shown in the patent to Odquist No. 2,312,357, dated March 2, 1943. However, the apparatus to Odquist presents a disadvantage because of its slow rate of gaging and classifying and because there is no means for desensitizing the gage when there is no sheet therein.

It is an object of my invention to provide apparatus which will automatically gage and classify sheet material.

This and other objects will be more apparent after referring to the following specification and attached drawings, in which:

The single figure is a schematic showing of the classifying apparatus and wiring diagram therefor.

Referring more particularly to the drawing, the reference numeral 2 indicates a motor driven conveyor over which sheets S, to be gaged and classified, pass in closely spaced relationship. The conveyor 2 is preferably a belt conveyor having a pair of spaced apart belts for supporting the sheets. The sheets S are fed from a pile 4 to the conveyor 2 and pass successively over a deflector gate 6, a motor driven conveyor 8, a deflector gate 10 and a third motor driven conveyor 12 into prime pile 14. The gates 6 and 10 are operated by means of solenoids 16 and 18, respectively. A motor driven conveyor 20 is located on the discharge side of conveyor 2 and feeds off-gage sheets into the off-gage pile 22. A similar conveyor 24 is located at the discharge end of conveyor 8 and directs off-gage sheets to the off-gage pile 26. A radioactive source 28 is located beneath the path of travel of the sheets S on the conveyor 2 and a pick-up head 30 for picking up the signal for the radioactive source 28 is arranged above the path of travel of the sheets S. The radioactive source 28 is connected to a gage control 32 which in turn is connected to a preamplifier 34. The gage head 30 is also connected to the preamplifier 34. An amplifier 36 and phase detector 38 are connected in series with the preamplifier 34. The parts 28, 30, 32, 34, 36 and 38 are parts of the standard gage shown in the Clapp and Bernstein patents discussed above. However, the gages disclosed in the patents depend upon averaging the actual measurements of the gage in a long length of strip being gaged. For example, at line speeds in the neighborhood of 1000 ft./min. approximately 30 feet of the strip is averaged. Such apparatus is not suitable for gaging sheets. A resistor 40 and condenser 42 are connected in series with phase detector 38. Normally closed contacts 44 and a meter 46 are connected in parallel with the condenser 42. A relay coil 48 controls the operation

2

of contacts 44. A light source 50 is located above the sheets S on the conveyor 2 a distance less than the length of a sheet from the pick up head 30. A photosensitive device 52 is mounted below the sheets S directly below the light source 50. A pulse lengthener 54 is connected to the photosensitive device 52 and the relay coil 48. The out-put of the gage circuit is connected to a control circuit 56 through a condenser 58 and a resistor 60. As shown, the control circuit 56 consists of an amplifier 62, a phase inverter 64, a potentiometer 66, a pulse lengthener 68 and a potentiometer 70 and pulse lengthener 72 connected in parallel with the potentiometer 66. The pulse lengtheners 68 and 72 are preferably of the type disclosed in my copending application, Serial No. 273,697, filed February 27, 1952, now Patent No. 2,655,620. The outputs of pulse lengtheners 68 and 72 are connected to solenoids 74 and 76 of a proportional timer 78 which is mechanically connected to be driven by the conveyor 2. This proportional timer is preferably of the type described in the patent to Ladach Patent No. 2,217,342 and is equipped with contact mechanism that energizes solenoids 16 and 18.

The operation of the device is as follows.

When there is no sheet in the gage the contact 44 will be closed so that the capacitor or condenser 42 will be shorted out and no voltage will appear across it. When a sheet enters the gage there will be no voltage across the capacitor 42 until the leading end of the sheet intercepts the light from light source 50. When this occurs the electronic pulse lengthener 54 is actuated by photocell 52 thus energizing relay coil 48 for a fixed period of time which is set to de-energize the relay before the trailing end of the sheet passes the beta-ray beam generated by the ray source 28. Energization of coil 48 opens contacts 44 and permits the signal from the preamplifier 34 to pass through amplifier 36, phase detector 38, resistor 40, condenser 42 and meter 46. If the sheet is on-gage the signal will be zero because the initial adjustment of the gage control 32 balances out the on-gage signal entering preamplifier 34. Thus no voltage will build up across the capacitor 42. If the sheet is too thick, a voltage of positive polarity will appear at the output of phase detector 38 and start charging capacitor 42 through resistor 40. The capacitor will charge for a short period of time, such as 0.1 second, after which the relay coil 48 is de-energized and the contacts 44 closed. Closing of contacts 44 quickly discharges capacitor 42 and produces a voltage pulse across capacitor 58 and resistor 60. The magnitude of the voltage pulse is a measure of the amplitude of the deviation in gage and its polarity is an indication of the direction of the deviation. The same pulse appears across meter 46 and indicates the magnitude and direction of deviation in gage. Shorting the capacitor 42 between each measurement insures that each sheet will be measured individually and will not be influenced by the measurement on the preceding sheet. The voltage that appears across capacitor 42 has a saw-tooth wave form, that is, it rises slowly and drops very rapidly when the short is applied by contact 44. This wave form is differentiated by capacitor 58 and resistor 60 and gives a voltage pulse across resistor 60 that is very sharp and has an amplitude and polarity determined by the deviation from normal gage. This pulse is amplified by amplifier 62 and transmitted through phase inverter 64 to potentiometer 66 and also potentiometer 70. Positive pulses from amplifier 62 passing through potentiometer 70, if of sufficient amplitude, will trigger pulse lengthener 72 which in turn will provide an out-put pulse of sufficient amplitude and duration to operate solenoid 76. Energization of solenoid 76 will cause the proportional timer 78 to energize solenoid 16 causing it to move the gate 6 to deflect the sheet into the off-gage pile 22. If the sheet is

too thin a negative pulse will be impressed on amplifier 62. This negative pulse will be inverted in phase inverter 64. This pulse, if of sufficient amplitude, will trigger pulse lengthener 68 and energize solenoid 74. Energization of solenoid 74 will cause proportional timer to energize solenoid 18 and divert the sheet to the off-gage pile 26. The potentiometers 66 and 70 will only operate their respective pulse lengtheners when a positive pulse is applied thereto so that there is no danger of both gates 6 and 10 opening at the same time. If desired, only a single off-gage pile may be used in which case pulse lengtheners 68 and 72 will be arranged so that either pulse lengthener will operate the one deflector gate. Potentiometers 66 and 70 may be set manually so that a signal of any desired amplitude will trigger the classifying pulse lengtheners. In other words these two potentiometers determine how much off-gage a sheet must be before it is rejected. Additional potentiometers may be added and set at different values to control other similar classifying circuits so that by adding additional piles the sheets could be separated into as many gages as desired.

While one embodiment of my invention has been shown and described it will be apparent that other adaptations and modifications may be made without departing from the scope of the following claims.

I claim:

1. Apparatus for automatically gaging sheets traveling successively in a given path of travel comprising a radioactive source located on one side of the path of travel of said sheets, means on the opposite side of the path of travel of said sheets for picking up the signal from said radioactive source, a circuit connected to said last named means including a phase detector, resistor and condenser connected in series, normally closed contacts connected in parallel with said condenser, a light source located less than the length of one sheet from said radioactive source on one side of the path of travel of said sheets, a photosensitive device located on the other side of the path of travel of said sheets opposite said light source, a circuit including said photosensitive device and means for opening said normally closed contacts when a sheet interrupts the light from said light source, and a meter connected in parallel with said condenser for measuring the gage of said sheets.

2. Apparatus for automatically gaging sheets traveling successively in a given path of travel comprising a radioactive source located on one side of the path of travel of said sheets, means on the opposite side of the path of travel of said sheets for picking up the signal from said radioactive source, a circuit connected to said last named means including an amplifier, a phase detector, resistor and condenser connected in series, normally closed contacts connected in parallel with said condenser, a light source located less than the length of one sheet from said radioactive source on one side of the path of travel of said sheets, a photosensitive device located on the other side of the path of travel of said sheets opposite said light source, a circuit including said photosensitive device, a pulse lengthener and a relay coil for opening said normally closed contacts when a sheet interrupts the light

from said light source, and a meter connected in parallel with said condenser for measuring the gage of said sheets.

3. Apparatus for automatically gaging and classifying sheets comprising a pair of conveyors arranged in tandem over which the sheets pass, a deflector between the conveyors for deflecting selected sheets from their path of travel, a radioactive source located on one side of the path of travel of said sheets over the first of said conveyors, means on the opposite side of the path of travel of said sheets over the first of said conveyors for picking up the signal from said radioactive source, a circuit connected to said last named means including a phase detector, resistor and condenser connected in series, normally closed contacts connected in parallel with said condenser, a light source located less than the length of one sheet from said radioactive source on one side of the path of travel of said sheets, a photosensitive device located on the other side of the path of travel of said sheets opposite said light source, a circuit including said photosensitive device and means for opening said normally closed contacts when a sheet interrupts the light from said light source, means for operating said deflector, a control circuit operable by the output of said first circuit for operating said deflector operating means when a sheet is off gage.
4. Apparatus for automatically gaging and classifying sheets comprising three conveyors arranged in tandem over which the sheets pass, a first deflector between the first two conveyors for deflecting selected sheets from their path of travel, a second deflector between the second and third conveyors for deflecting selected sheets from their path of travel, a radioactive source located on one side of the path of travel of said sheets over the first of said conveyors, means on the opposite side of the path of travel of said sheets over the first of said conveyors for picking up the signal from said radioactive source, a circuit connected to said last named means including an amplifier, phase detector, resistor and condenser connected in series, normally closed contacts connected in parallel with said condenser, a light source located less than the length of one sheet from said radioactive source on one side of the path of travel of said sheets, a photosensitive device located on the other side of the path of travel of said sheets opposite said light source, a circuit including said photosensitive device and a relay coil for opening said normally closed contacts when a sheet interrupts the light from said light source, separate means for operating each of said deflectors, a control circuit operable by the output of said first circuit for operating one of the deflector operating means when a sheet is off gage in one direction and a control circuit operable by the output of said first circuit for operating the other deflector operating means when a sheet is off gage in the other direction.
